UNITED STATES PATENT OFFICE.

CHARLES LE ROY HOLDEN AND WILLIAM KNEDLER, OF KINGS MILLS, OHIO, ASSIGNORS TO THE PETERS CARTRIDGE COMPANY, OF CINCINNATI, OHIO, A CORPORATION OF OHIO.

BULLET.

Application filed August 17, 1922. Serial No. 582,538.

To all whom it may concern:

Be it known that we, CHARLES LE ROY HOLDEN and WILLIAM KNEDLER, citizens of the United States, residing at Kings Mills, in the county of Warren and State of Ohio, have invented certain new and useful Improvements in Bullets, of which the following is a specification.

Our invention relates to bullets or balls for cartridges such as are used in rifles, pistols, and the like, and has for one of its objects the provision of simple and efficient means for rendering a bullet highly effective for holding itself intact and in shape during flight.

A further object is the provision of a bullet of this character having great piercing power.

A further object is the provision of a bullet of this character adapted to have maximum spreading or expanding power upon engaging a target.

A still further object is the provision of means for encasing air or other fluid in the front end of a bullet in a manner to cause such air to facilitate expanding or flattening the bullet upon the latter engaging a target.

Other objects will appear hereinafter.

An embodiment of our invention is illustrated in the accompanying drawing forming a part of this specification and in which—

Fig. A is a central section of a reinforcing or protecting member used in our improved construction;

Fig. B is a similar view of a tip used in our construction;

Fig. C is a central section of the entire assembled bullet embodying our invention;

Fig. D is an end elevation of the base of the bullet;

Fig. E is a side view of said bullet; and

Fig. F is a view similar to Fig. C but omitting the protecting member shown in Fig. A.

Referring more particularly to the drawing, we have indicated a core or central part of a bullet which may be of any approved material. The core 1 is provided with a protecting member 2 which may be of any desired sheet material struck up, substantially as indicated, and fitted over the front end of the core 1. The core 1 is preferably provided with a recess 1' in its front end

and the protecting member 2 has a portion 2' disposed in the recess 1', substantially as indicated in Fig. C. The protecting member 2 is preferably of a material having sufficient rigidity and strength to hold the core 1 against flattening or expanding during flight. The member 2 is also of a material which will be easily flattened out when the bullet strikes a target.

The type of bullet shown is an encased bullet in which the core is enclosed in a casting or jacket 3. In Fig. C the jacket also encloses the member 2. In Fig. F member 2 is dispensed with and the jacket fits the core 1, substantially as indicated.

A tip 4 is provided with a hollow portion 5. The tip is preferably conical in shape and has its base portion disposed within the jacket 3 and over the protecting member 2 in the construction shown in Fig. C, within the jacket 3 and engaging the core 1 in the construction shown in Fig. F, to form a fluid-tight joint for the tip 4 in both constructions. With this arrangement a quantity of air is pocketed in the hollow portion 5 and recess in the front end of the core 1. We preferably seal a quantity of air in the hollow portion 5 and recess 1', but any other fluid may be sealed in this space when so desired. The important feature is that the imprisonment of such fluid facilitates holding the bullet in its original shape during flight, and upon contacting a target the tip 4 will be crushed and the compression of the fluid in said space will facilitate spreading the front end of the core 1 and jacket 3. The fluid will tend to be driven through the core 1, thus giving a maximum flattening or mushrooming effect to the bullet when the latter engages a target. This gives great killing power to the bullet when the latter is used for hunting game, and the like.

The construction indicated in Fig. C is particularly adaptable to high velocity bullets or balls, the protecting member 2 and point 4 effectively holding the bullet in shape to obtain maximum results. In bullets or balls having lower velocity the protecting member 2 may be dispensed with, as indicated in Fig. F.

We have not indicated a shell charged with powder or a primer since our improved bullet is applicable to any of the ordinary shells now in use.

So-called "soft point," "mushroom," or

"expanding tip" bullets have in general possessed many defects among which are inaccuracy, failure to penetrate before expanding, penetration without expansion, and breaking up into small or large pieces when expanding or before striking the target, especially when fired at high velocities. The latter defect is usually caused by a weakness in the internal construction of the bullet. Our expanding tip bullet is of such improved construction that it overcomes these defects and functions with uniform excellence.

Especially our invention consists of enclosing the forward end of the bullet core in a metallic cup so that when the bullet is fired the tip first penetrates the target, then as the resistance becomes sufficient the tip collapses, the air in the sealed chamber becomes compressed to a degree sufficient to flatten or spread out the forward end of the bullet core and burst open the mouth or open end of the bullet jacket thus, together with the impact, causing the effect known as "mushrooming," which gives very deadly execution in hunting game of various kinds, especially big game. Our invention shows improvements in penetration, accuracy, the important property of preserving the same weight or mass of the bullet after firing as before, the bullet becoming "mushroomed" or expanded to a greater extent so that the wound inflicted upon the target is exceptionally large, deadly and disastrous. Moreover, the bullet in preserving its unity on impact despite high velocities and not becoming broken has greater penetration after mushrooming, thus greatly enhancing its killing power.

The various parts of the bullet may be made from any materials which may be found suitable for the purposes, for instance, the core 1 is preferably lead, the jacket 3 of brass, the tip 4 of brass, and the protecting member 2 of brass.

We claim:—

1. A bullet comprising a core having a recess in its forward end, a tip attached to and overlapping the front end of the core and confining a quantity of fluid in said recess and a jacket for said core the front end of said jacket overlapping the rear portion of said tip.
2. A bullet comprising a core having a recess in its front end, and a substantially conical-shaped tip member attached to the front end of the core and provided with a recess therein opposite the recess in the core, said tip overlapping the front end of said core and forming a substantially fluid-tight joint between the tip and core.
3. A bullet comprising a core having a recess in its front end, a tip conical in shape

with its base portion attached to and overlapping the core and providing a substantially fluid-tight joint between the core and tip, and a casing around said core with its front end disposed over and attached to said tip.

4. A bullet comprising a core having a recess in its front end, a hollowed out conical-shaped tip having its base portion overlapping said core with the interior of said tip communicating with said recess, and a casing enclosing the core and having a portion disposed over the rear of said tip, the connection between the tip and said core and recess providing a substantially fluid-tight joint so as to confine a quantity of fluid in the tip and said recess.

5. A bullet comprising a core having a depression in its front end, a protecting member of sheet material disposed over the front end of said core with a depression therein disposed within said recess, and a pointed tip having a hollowed out portion opposite said recess, there being a substantially fluid-tight joint between said tip and said protecting member.

6. A bullet comprising a shell, a core disposed within the shell and having a depression in its front end, a thin protecting member disposed over the front end of the core in said shell with a portion thereof disposed in said depression, and a tip substantially conical in shape and hollowed out with the base portion thereof disposed between said shell and said thin protecting member, there being a fluid-tight joint between the tip and said shell and protecting member sealing a fluid in said recess and the hollow part of said tip.

7. A bullet comprising a core member, a casing enclosing said core member, and a hollow pointed tip having its rear portion fitted over the front end of said core member and forming a lapped joint with said casing adjacent the forward end of said core member and providing a closed chamber within said tip and at the front end of said core member.

8. A bullet comprising a core member, a casing enclosing said core member, a sheet metal cover disposed over the forward end of said core member, and a hollow pointed tip overlapping the forward portion of said core member and sheet metal cover and arranged in overlapping relation with said casing providing a closed chamber within said tip and at the forward end of said core member.

In testimony whereof we have signed our names to this specification on this 31st day of July, A. D. 1922.

CHARLES LE ROY HOLDEN,
WILLIAM KNEDLER.
